APPARATUS FOR CONVEYING AND
TREATING ARTICLESWilliam H. Wilcox, Stockton, Calif., assignor to
California Cedar Products Company, a corpora-
tionOriginal application August 6, 1940, Serial No.
351,562. Divided and this application Novem-
ber 4, 1941, Serial No. 417,788

5 Claims. (Cl. 91—37)

This invention relates to improved conveying and treating apparatus for performing a certain portion of a manufacturing process, and in particular the invention is directed to a unique mechanical assembly for treating pencil slats during the course of the manufacture thereof.

This application is a division of my copending application on "Slat feeding apparatus," Ser. No. 351,562, filed August 6, 1940, now U. S. Patent No. 2,275,709, dated March 10, 1942.

In the manufacture of pencil slats, the individual slats are cut from blocks by gang saws; the individual slats emerging from the saws in block shaped groups wherein the slats engage each other in face to face relation. In other words, the individual slats in each group remain in the same relation to each other as the material forming the same existed in the integral block.

It has been found desirable to maintain the individual slats in such groups to the extent possible in the course of manufacture whereby to effectuate improved handling technique, inspection and grading by block characteristics rather than individual slat characteristics, and similar advanced manufacturing operations. However, during manufacture there are one or more operations which may preferably be carried out with the individual slats separated from each other; one such operation being the application of the wax to the slats.

It is the principal object of this invention to provide a unique mechanical assembly which is operative to separate the individual but initially engaged articles—such as pencil slats—of a group, to then treat the separated articles with a processing material, and to thereafter return the articles into such initial position as a group, and wherein each article occupies the same relative position as at the outset.

Another object of the invention is to provide apparatus as above which is arranged to effect a continuous advancing movement of the articles while the latter are being separated, treated and returned to the group; the apparatus advancing the articles, when separated, a predetermined distance.

A further object of the invention is to provide apparatus which is operative to separate the individual but initially engaged pencil slats of a group, to apply a quantity of processing fluid to each slat while thus separated, and to thereafter reengage the processed slats into said group.

It is also an object of this invention to provide apparatus which is operative to separate the individual but initially engaged pencil slats of a

group, to apply a quantity of fluid but solidifiable wax to each slat while separated, and to thereafter reengage the waxed slats into said group, the apparatus preferably being timed to reengage the slats while the wax is fluid or plastic, whereby upon solidification thereof, the slats of the group are adhered together.

10 A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a side elevation, mainly diagrammatic, or the apparatus.

20 Figure 2 is a fragmentary, enlarged elevation of a portion of the slat separating unit of the apparatus.

25 Referring now more particularly to the characters of reference on the drawing, a group of slats S in face to face engagement and as cut from a block, are conveyed from the gang saw (not shown) by means of conveyors 1 and 2 into a slat or group turn-over device indicated at 3 which rotates the group 90° from its initial position with the engaged slats vertical and resting on their side edges to a horizontal or stacked position as shown in Fig. 1.

30 This slat or group turn-over device, together with the remainder of the apparatus, is shown and described in full in the above identified copending application, and therefore a general description of the structural assembly will suffice for the purpose of this application.

35 When the group of slats S is turned to and supported in horizontal position, the then vertical side 3a of turn-over device 3 against which the group rests, is aligned with a fixed upstanding back plate 4 which extends some distance beyond device 3. A full length slat supporting strip 5 projects laterally and horizontally from the back plate in a plane to receive the lowermost slat of the group when advanced from the then horizontal group supporting flange 3b of device 3.

40 As a group of slats S so advance, they are engaged and received by an initial slat guiding and separating unit, indicated generally at 6, which includes, with strip 5, a plurality of vertically spaced, horizontal, and diverging strips 7 projecting laterally in fixed relation from back plate 4 above said strip 5. From this unit 6, the advanc-

ing slats are fed into the main or final slat separating unit, indicated generally at 8, which includes, with strip 5, a plurality of other similar strips 9 which project from the back plate and extend from adjacent unit 6 to substantially the remote end of said back plate; said strips 9 diverging from each other for some distance, then extending straight and parallel for some distance, as indicated at 10, and then converging to a termination in such closely spaced relation as to return the slats practically together again. From this termination the slats advance, again in a group and in the same relation as at the start, onto a receiving platform 11, which may be one end of strip 5.

While the separated slats are moving along the straight portions 10, they may be inspected or treated individually, and in the present embodiment the slats are individually waxed on their upper face by suitable means here diagrammatically shown, as being a brush 12 for each slat, receiving normally solid wax in a molten condition from a tank 13 supported behind the back plate. The speed of advance of the slats from brushes 12 to platform 11 is such that the slats reengage as a group before the wax solidifies, whereby upon solidification thereof the slats of each group are firmly adhered together, facilitating handling, bundling, etc.

The slats are transferred from turn-over device 3 onto the unit 6, and carried through guiding and separating units 6 and 8, by means of mechanism which includes a vertically spaced pair of driven chains 14 mounted on end sprockets 15 and having their runs horizontal, parallel to, and laterally out from back plate 4; said runs extending from ahead of device 3 to a point adjacent and below platform 11. Upstanding rods 16 are mounted at intervals on the chains; such rods being of a height somewhat greater than unit 8 and engaging each group of slats on device 3 and advancing said slats through units 6 and 8. The slats overhang the strips of the units, and the rods engage the rear end of the overhanging portion of said slats.

The chains 14, together with conveyors 1 and 2, are driven in timed relation from a motor 17 through the medium of a drive assembly indicated generally at 18.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure

from the spirit of the invention, as defined by the appended claims.

Having thus described my invention, what I claim as new and useful and desire to secure by Letters Patent is:

1. Conveying and treating apparatus comprising means to initially support a group of like elements with given surfaces thereof in closely adjacent predetermined relationship to each other, means to advance the group of elements as a unit for a predetermined distance, means acting on the elements as they are advanced to first separate and then bring them together again with said surfaces positively in said predetermined relationship to each other, and means to treat the elements when they are separated.

2. Conveying and treating apparatus comprising means to initially support a group of like elements with given surfaces thereof in closely adjacent predetermined relationship to each other, means to advance the group of elements as a unit for a predetermined distance, means acting on the elements as they are advanced to first separate and then bring them together again, and means operative to apply a treating material to the elements when they are separated.

3. Conveying and treating apparatus comprising means to initially support a group of slats in a close face to face and otherwise predetermined relationship to each other, means to advance the slats as a unit for a predetermined distance, means acting as the slats are advanced to first separate and then bring them together again in said face to face and predetermined relationship, and means to apply wax to one face of the slats when they are separated.

4. Conveying and treating apparatus comprising means to initially support a group of slats in close face to face relationship, means to advance the slats as a unit for a predetermined distance, means acting as the slats are advanced to separate them in a vertical direction while maintaining the slats substantially horizontal, and means to treat one face of the slats while they are thus separated.

5. Conveying and treating apparatus comprising means to initially support a group of like elements in closely adjacent relationship, means to advance the group of elements as a unit for a predetermined distance, means acting on the elements as they are advanced to first separate and then bring them together again, and means disposed to project between the elements and treat an adjacent surface thereof when they are separated.

WILLIAM H. WILCOX.
